RECEPTACLE PANEL FOR A TRAY

Harry A. Tomarin, Cincinnati, Ohio, assignor to Loroco Industries Incorporated, Reading, Ohio, a corporation of Ohio

Application January 27, 1955, Serial No. 34,261

Term of patent 14 years

(Cl. D44—10)

Fig. 1 is a plan view of a receptacle panel for a tray, showing my new design.

Fig. 2 is a perspective view of the device of Fig. 1.

Fig. 3 is a sectional view taken on line 3—3 of Fig. 1.

The dominant features of the design are shown in full lines in the drawing.

I claim:

The ornamental design for a receptacle panel for a tray, as shown and described.
